UNITED STATES PATENT OFFICE

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA

COKE OVEN

Application filed June 21, 1926. Serial No. 117,216.

My invention comprehends broadly certain improvements of general utility in the coke oven art and in its more specific aspects relates to the generation, separation and utilization of gases produced in the coking chambers of vertical retorts. The subject matter of this application is broadly related to that of my former applications, Serial No. 684,842, filed January 4, 1924, and Serial Nos. 1,717 and 1,718, filed January 12, 1925, of which applications my present application is a continuation in part.

The gas of distillation taken off the fresh coal in systems of the character indicated is rich in B. t. u. value and since most of the municipalities of this country require that the gas sold to the public be of such character it has high commercial value which has led to the discontinuance of its use, so far as practicable, in firing the heating walls of the retorts in order that it may be saved for sale, a cheaper and leaner gas, such as producer gas, being usually employed to fire the retort walls. This, however, ordinarily requires the construction and operation of a so-called producer, the gas from which by reason of its high nitrogen content must of necessity be preheated in the regenerators before it can be burned. This adds materially to construction and operation costs.

My present invention contemplates dispensing with the necessity for a separate producer and generating the necessary auxiliary gas for heating the flued walls in the oven chambers themselves. I am thereby enabled not only to materially reduce construction and operation costs but also to preserve the major portion of the valuable gases of distillation for sale. These results I accomplish by introducing into the portion of the oven chambers below their tops which is occupied by incandescent coke, a medium which will react with the heated coke to generate a combustible gas which is removed from the oven chambers at a point below that at which the gases of distillation are primarily released and removed. I may, for instance, introduce steam into the region of incandescent coke and remove therefrom the resultant water gas which is itself of fairly high B. t. u.

value and does not require preheating before its introduction into the flued heating walls. This gas as it is taken from the oven is preferably passed through coolers to reduce its temperature and from thence it is led through suitable piping to the flued heating walls, a portion preferably being passed to a suitable reservoir to equalize the pressure on and thus to stabilize the operation of the flues. Where the gases of distillation are higher in B. t. u. value than is necessary a regulated portion of the water gas may be allowed to ascend to the top of the oven chamber and mix therewith in the necessary proportion to give the resultant quality of gas desired. For the production of the desired quantity of water gas I prefer to utilize steam which has been employed to cool the coke in the extractor magazine, supplemented by additional steam as may be necessary.

It will be obvious that to decompose the steam into water gas in the region of the incandescent coke in the oven chamber while at the same time maintaining coking temperature there necessitates the supplying from the adjacent region of the oven walls heat additional to that required for completing the coking and this in turn necessitates regulation of the combustion in this region of the wall flues to supply the proper total amount of heat required for both purposes.

In systems that burn up and down and have separate regulators for each stage of combustion if it is desired to make an appreciable amount of water gas in the lower part of the coking chamber, requiring the addition of more heat to that part, there results an unbalancing of the system on reversals. The regenerator groups employed for preheating the combustible gases and air on downflow and upflow respectively are unequally heated by the outflowing waste gases and those groups which are required to preheat larger quantities of combustible gases on upflow are heated to a lower temperature than those which are required to preheat smaller quantities of combustible gases on downflow, whereas the reverse should obvi-

ously be true. It follows that the heat distribution of the system is totally unbalanced.

All these disadvantages are avoided by my system and I am able to obtain a balanced heating throughout, both on upflow and on downflow. This I accomplish by providing upper and lower heating stages for the flues of my heating walls, the lower stages being regulatable as to the flow of their combustible gases independently of the upper stages. I am thus enabled to maintain the temperature of the upper stages sufficiently low to prevent cracking of the gases of distillation released in the top of the oven chamber while at the same time I independently regulate the combustion in the lower stages to produce the quantity of heat requisite for proper coking and simultaneously that requisite for the decomposition of steam into water gas. Moreover, since I am able to maintain the distribution of the heat of combustion of the heating walls the same on reversals and since the respective regenerator groups each receive in alternation the combined waste gases of combustion from both the upper and the lower stages of the heating walls both groups are equally heated in alternation by said waste gases and my regenerator system is perfectly balanced on upflow and on downflow.

It will be obvious that a battery embodying my improvements is of great flexibility, being capable of operation either on coke oven gas alone introduced without preheating through the usual channels and nozzles in the bed of the oven or by water gas alone generated as above indicated which also needs no preheating and may be introduced through the same channels as the coke oven gas, or by a mixture of the two gases, and lastly it may be heated by producer gas or other extraneously derived gas, the latter being passed through appropriate regenerators to preheat the same.

My invention further consists in such other new and useful improvements or advantages in construction and operation as are found to obtain in the structure and devices hereinafter described or claimed.

While, as a specific embodiment, I have disclosed the principles involved in my invention applied to a continuous coking retort it will be obvious to those skilled in the art that they are applicable to other coke oven structures or to other heat treating apparatus.

In the accompanying drawings, forming a part of this specification and showing for purposes of exemplification a preferred form and manner in which the invention may be embodied and practiced, but without limiting the claimed invention specifically to such illustrative instance or instances:

Figure 1 is a vertical section transversely of the oven showing the application of my invention to a vertical retort.

Fig. 2 is a front elevation of the same, and Fig. 3 is a composite horizontal section

taken on different horizontal planes indicated by the lines A—A, B—B and C—C respectively of Fig. 1.

The same characters of reference designate the same parts in each of the several views.

In the illustrated embodiment of the invention there is shown a vertical retort provided with the usual coking chambers 11 alternating with vertically flued heating walls 12. At the base of each coking retort is located a coke extractor magazine 16 provided with suitable steam pipes 18 for the introduction of steam thereinto for cooling the coke in the magazine and for reacting with incandescent coke in the retort chamber to generate water gas. Located at a point in the oven chamber, preferably just below the plastic zone and in the upper region of the incandescent coke, is a water gas offtake 19 and at the top of the oven is the usual offtake 20 leading into the main 21 for the removal of the rich gases of distillation.

In order to independently regulate the temperature of the several zones of the oven chamber I preferably divide each flued heating wall into two stages, the upper comprising the flue sections 37 and the lower the flue sections 38 interconnected by the channels 40. The flues of the lower section at their lower end communicate by means of the ports 42 with the channel 43 which in turn communicates with the channel 44 passing around an oven chamber and constituting a flow connection between the lower end of the flues of one wall and the lower ends of the flues of the other wall on the opposite side of the oven chamber. Regenerators are shown at 45 provided with the usual checker-work 46, said regenerators being arranged in pairs communicating with individual heating walls respectively, as set forth more in detail in my application 684,342, supra. In accordance with this arrangement when operating on producer gas, the latter is introduced into a heating wall through one regenerator of a pair, while air is introduced thereinto through the other regenerator of the same pair in the same heating wall and the waste gases are removed through the flues of an opposite heating wall and through the pair of regenerators connected thereto. When coke oven gas is employed additional air replaces the producer gas of the former arrangement, the coke oven gas being directly introduced into the flues through appropriate flues as hereinafter set forth. Referring to Fig. 3, if it be assumed that the regenerator indicated P is operated to preheat gas and that indicated A to preheat air the flow of air will be from A through the upper duct 53 to the horizontal flue 54 through the ports 55 into the tops of the upper flue sections 37 of the corresponding heating walls, and the flow of producer gas will be from regenerator P through the duct 63, the horizontal flue 64 and ports 65 into

130

the tops of the same upper flue sections 37. The flow of the air and the flow of the producer gas to the upper flue sections 37 are independently regulated by the respective sets of sliding bricks 69. In order to supply the lower flue sections 38 the ports 71 communicably connect the horizontal channel 54 with the vertical feed channels 72 located in the bottle bricks 73 and the ports 81 connect 10 the horizontal channel 64 with the vertical feed channels 82 similarly located. These vertical feed channels communicate through branch ducts 74 and 84 with the tops of the lower flue sections 38. The flow of air 15 through the vertical feed channels 72 and the flow of producer gas through the vertical feed channels 82 are independently regulated by the respective sets of sliding bricks 85 located in the horizontal flues 54 and 64, respectively, 20 within easy reach of the oven top.

In accordance with my invention the water gas generated by the reaction of steam on the incandescent coke is taken off through the offtake 19 and from thence is led through the pipe 86 to the cooler 87, from thence it is led by pipe 88, in which is located a pump 89, to a reservoir (not shown) and to branch pipes 90, 90' and 90''. From the branch pipe 90' the gas is led through branches provided with 25 regulating devices 91 to the channels 92 communicating with the upper ends of the upper flue sections 37 and from the branch pipe 90'' gas is similarly led through regulating devices 93 to channels 95 communicating with 30 the upper ends of the lower flue sections 38. The channels 92 and 95, also have connection (not shown) with the coke oven gas main or similar sources of supply whereby, when the 35 water gas connections are shut off, the oven may be operated on coke oven gas or a mixture of the two may be employed.

In the operation of my oven the flued walls may be heated by the combustion of producer gas in the presence of air in the usual manner, both being preheated in their respective regenerators, or I may alternatively introduce water gas generated in the oven itself as hereinbefore set forth through the channels 92 and 95, or as a still further mode of operation 45 I may shut off the latter supply from the channels 92 and 95 and introduce therein the coke oven gas itself, or again, I may use a mixture of the several gases in the proportions desired. The introduction of steam 50 into the incandescent region of the coking chamber for the production of water gas will obviously tend to reduce the temperature in that section of the oven, seriously interfering with the coking operation, and were it attempted to supply additional heat in all of 55 the flues in order to maintain a coking temperature the heat generated in the upper flue sections 37 might be so great as to cause a cracking of the rich gases of distillation with 60 its well known attendant disadvantages. By

my system, however, I am enabled to preserve the temperature of the region of the oven in which the gases of distillation for the most part are generated at the desired temperature to prevent cracking while at 70 the same time I may by independent regulation of the inflowing gases into the lower flue sections 38 increase the amount of the heat generated in said section and thereby supply the additional heat required in the incandescent region of the coking charge to generate the water gas employed by me to heat the oven walls. It will therefore be obvious that my system is of great simplicity and extremely flexible in use. 75

The invention as hereinabove set forth is embodied in a particular form of construction, but may be variously embodied within the scope of the claims hereinafter made. 80

I claim:

1. In a vertical retort battery for the carbonization of coal, in combination: a plurality of side-by-side continuous vertical coking chambers each adapted to receive through its top substantially continuously the charge 90 to be coked and to discharge through its bottom substantially continuously the coked charge; heating walls therefor between and contiguous to said coking chambers and respectively comprising vertical flame flues; 95 regenerators communicably connected with the flame flues of the respective heating walls; each of said heating walls having its vertical flame flues disposed in upper and lower flue sections which respectively have 100 fuel gas conduits and air regenerator conduits, adapted for separately regulating the heating of said sections so that the upper portions of the coking chambers may be regulably heated for coal gas production and 105 the lower portions for water gas production, and each of the heating walls having flow duct means common to and in communication with both flue sections for commingling and passing waste gases therefrom to said 110 regenerators; distillate-gas offtake means communicably connected with the upper portions of said coking chambers for offtake of coal-gases of distillation at the upper parts of said coking chambers; means for introducing steam into the lower portions of said coking chambers for water gas production in the lower portions thereof; water-gas offtake means communicably connected with the coking chambers below said distillate-gas offtake means and above said means for introducing steam, and adapted for offtake from 115 said coking chambers, separately from and independently of gas off-flow through the distillate gas offtake means for the coking chambers, of water gas produced in the lower portions of said coking chambers from said steam; and means for leading water-gas from said water-gas offtake means to the fuel gas conduits of at least one of said upper 120 125 130

and lower flue sections of each of the heating walls for combustion in the flues of said sections.

2. In a vertical retort battery for the carbonization of coal, in combination: a plurality of side-by-side continuous vertical coking chambers each adapted to receive through its top substantially continuously the charge to be coked and to discharge through its bottom substantially continuously the coked charge; heating walls therefor between and contiguous to said coking chambers and respectively comprising vertical flame flues; regenerators communicably connected with the flame flues of the respective heating walls; each of said heating walls having its vertical flame flues disposed in upper and lower flue sections which respectively have fuel gas conduits and air regenerator conduits, adapted for separately regulating the heating of said sections so that the upper portions of the coking chambers may be regulably heated for coal gas production and the lower portions for water gas production, and each of the heating walls having flow duct means common to and in communication with both flue sections for commingling and passing waste gases therefrom to said regenerators; distillate-gas offtake means communicably connected with the upper portions of said coking chambers for offtake of coal-gases of distillation at the upper parts of said coking chambers; means for introducing steam into the lower portions of said coking chambers for water gas production in the lower portions thereof; water-gas offtake means communicably connected with the coking chambers below said distillate-gas offtake means and above said means for introducing steam into the lower portions of said coking chambers, separately from and independently of gas off-flow through the distillate gas offtake means for the coking chambers, of water-gas produced in the lower portions of said coking chambers from said steam; and means for leading water-gas from said water-gas offtake means.
5. In a vertical retort battery for the carbonization of coal, in combination: a plurality of side-by-side continuous vertical coking chambers each adapted to receive through its top substantially continuously the charge to be coked and to discharge through its bottom substantially continuously the coked charge; heating walls therefor between and contiguous to said coking chambers and respectively comprising vertical flame flues; regenerators communicably connected with the flame flues of the respective heating walls; each of said heating walls having its vertical flame flues disposed in upper and lower flue sections which respectively have fuel gas conduits and air regenerator conduits, adapted for separately regulating the heating of said sections so that the upper portions of the coking chambers may be regulably heated for coal gas production and the lower portions for production of a leaner gas formed by reaction of incandescent coke in said retorts with a fluid medium introduced therein, and each of the heating walls having flow duct means common to and in communication with both flue sections for commingling and passing waste gases therefrom to said regenerators; distillate-gas offtake means communicably connected with the upper portions of said coking chambers for offtake of coal-gases of distillation at the upper parts of said coking chambers; means for introducing steam into the lower portions of said coking chambers for water gas production in the lower portions thereof; water-gas offtake means communicably connected with the coking chambers below said distillate-gas offtake means and above said means for introducing steam into the lower portions of said coking chambers, separately from and independently of gas off-flow through the distillate gas offtake means for the coking chambers, of water-gas produced in the lower portions of said coking chambers from said steam; and means for leading water-gas from said water-gas offtake means.
3. The combination as defined in claim 2 in which means are provided for cooling the water gas after it leaves the coking chambers and while being led to the rich fuel gas conduits so that the water gas may enter said conduits and flues in unpreheated condition.
4. In a vertical retort battery for the carbonization of coal, in combination: a plurality of side-by-side continuous vertical coking chambers each adapted to receive through its top substantially continuously the charge to be coked and to discharge through its bottom substantially continuously the coked charge; heating walls therefor between and contiguous to said coking chambers and

- gases of distillation at the upper parts of said coking chambers; means for introducing a fluid medium into the lower portions of said coking chambers for reaction with incandescent coke therein to produce a leaner gas than coal gas in the lower portions of said coking chambers; lean gas offtake means communicably connected with the coking chambers below said distillate-gas offtake means and above said means for introducing a fluid medium, and adapted for offtake from said coking chambers, separately from and independently of gas off-flow through the distillate gas offtake means for the coking chambers, of leaner gas produced in the lower portions of said coking chambers from said fluid medium; and means for leading lean gas from said lean gas offtake means to the fuel gas conduits for said upper and lower flue sections of each of the heating walls for combustion in the flues of said sections. 5
6. In a vertical retort battery for the carbonization of coal, in combination: a plurality of side-by-side continuous vertical coking chambers each adapted to receive through its top substantially continuously the charge to be coked and to discharge through its bottom substantially continuously the coked charge; heating walls therefor between and contiguous to said coking chambers and respectively comprising vertical flame flues; regenerators communicably connected with the flame flues of the respective heating walls, and arranged and adapted for respectively supplying preheated air and producer gas or jointly supplying preheated air; each of said heating walls having its vertical flame flues disposed in upper and lower flue sections which respectively have rich fuel gas conduits and regenerator conduits, adapted for separately regulating the heating of said sections so that the upper portions of the coking chambers may be regulably heated for coal-gas production and the lower portions for water-gas production, and each of the heating walls having flow duct means common to and in communication with both flue sections for commingling and passing waste gases therefrom to said regenerators, and the regenerator conduits being arranged and adapted for respectively supplying preheated air and gas or jointly supplying preheated air; distillate-gas offtake means communicably connected with the upper portions of said coking chambers for offtake of coal-gases of distillation at the upper parts of said coking chambers; means for introducing steam into the lower portions of said coking chambers for water gas production in the lower portions thereof; water-gas offtake means communicably connected with the coking chambers below said distillate-gas offtake means and above said means for introducing steam, and adapted for offtake from said coking chambers, separately from and independently of gas off-flow through the distillate gas offtake means for the coking chambers, of water gas produced in the lower portions of said coking chambers from said steam; and means for leading water-gas from said water gas offtake means to the rich fuel gas conduits for said upper and lower flue sections of each of the heating walls for combustion in the flues of said sections. 10
7. In a vertical retort battery for the carbonization of coal, in combination: a plurality of side-by-side continuous vertical coking chambers each adapted to receive through its top substantially continuously the charge to be coked and to discharge through its bottom substantially continuously the coked charge; heating walls therefor between and contiguous to said coking chambers and respectively comprising vertical flame flues; regenerators communicably connected with the flame flues of the respective heating walls, and arranged and adapted for respectively supplying preheated air and producer gas or jointly supplying preheated air; each of said heating walls having its vertical flame flues disposed in upper and lower flue sections which respectively have rich fuel gas conduits and regenerator conduits, adapted for separately regulating the heating of said sections so that the upper portions of the coking chambers may be regulably heated for coal-gas production and the lower portions for water-gas production, and each of the heating walls having flow duct means common to and in communication with both flue sections for commingling and passing waste gases therefrom to said regenerators, and the regenerator conduits being arranged and adapted for respectively supplying preheated air and gas or jointly supplying preheated air; distillate-gas offtake means communicably connected with the upper portions of said coking chambers for offtake of coal-gases of distillation at the upper parts of said coking chambers; means for introducing steam into the lower portions of said coking chambers for water gas production in the lower portions thereof; water-gas offtake means communicably connected with the coking chambers below said distillate-gas offtake means and above said means for introducing steam, and adapted for offtake from said coking chambers, separately from and independently of gas off-flow through the distillate gas offtake means for the coking chambers, of water gas produced in the lower portions of said coking chambers from said steam; and means for leading water-gas from said water gas offtake means to the rich fuel gas conduits for said upper and lower flue sections of each of the heating walls for combustion in the flues of said sections. 15
8. In a vertical retort battery for the carbonization of coal, in combination: a plurality of side-by-side continuous vertical coking chambers each adapted to receive through its top substantially continuously the charge to be coked and to discharge through its bottom substantially continuously the coked charge; heating walls therefor between and

- contiguous to said coking chambers and respectively comprising vertical flame flues; regenerators communicably connected with the flame flues of the respective heating walls, and arranged and adapted for respectively supplying preheated air and producer gas or jointly supplying preheated air; each of said heating walls having its vertical flame flues disposed in upper and lower flue sections which respectively have fuel gas conduits for supply of coke oven gas and of water gas, and regenerator conduits, adapted for separately regulating the heating of said sections so that the upper portions of the coking chambers may be regulably heated for coal gas production and the lower portions for water-gas production, and each of the heating walls having flow duct means common to and in communication with the bottoms of both flue sections for commingling and passing waste gases therefrom to said regenerators; distillate-gas offtake means communicably connected with the upper portions of said coking chambers for offtake of coal-gases of distillation therefrom at the upper parts of said coking chambers; means for introducing steam into the lower portions of said coking chambers for water gas production in the lower portions thereof; water-gas offtake means communicably connected with the coking chambers below said distillate-gas offtake means and above said means for introducing steam, and adapted for offtake from said coking chambers, separately from and independently of gas off-flow through the distillate gas offtake means for the coking chambers, of water-gas produced in the lower portions of said coking chambers from said steam; and means for leading water gas from said water-gas offtake means to the rich fuel gas conduits for said upper and lower flue sections of each of the heating walls for combustion in the flues of said sections.
10. In a vertical retort battery for the carbonization of coal, in combination; a plurality of side-by-side continuous vertical coking chambers each adapted to receive through its top substantially continuously the charge to be coked and to discharge through its bottom substantially continuously the coked charge; heating walls therefor between and contiguous to said coking chambers, each of said heating walls comprising upper and lower sets of vertical flues communicably connected with each other for passage of combustion products from one to the other; duct means communicably connecting the flues in each of said heating walls with the flues in another of the heating walls, said duct means being in communication with the lower ends of the lower sets of flues of the heating walls they respectively connect; paired regenerators having connections separately communicating with the flame flues of the heating walls, respectively, the connections of said regenerators providing separate ducts for and in communication with the tops of the upper and the lower sets of flues; distillate-gas offtake means communicating with said coking chambers at their upper ends for collecting gases of distillation therefrom; means for introducing a fluid medium into the lower ends of said coking chambers to react with incandescent coke therein to form a lean combustible gas; lean gas offtake means in communication with said coking chambers be-
- 5 10 15 20 25 30 35 40 45 50 55 60 65 70 75 80 85 90 95 100 105 110 115 120 125 130
9. In a vertical retort battery for the carbonization of coal, in combination: a plurality of side-by-side continuous vertical coking chambers each adapted to receive through its top substantially continuously the charge to be coked and to discharge through its bottom substantially continuously the coked charge; heating walls therefor between and contiguous to said coking chambers and respectively comprising vertical combustion flues; regenerators communicably connected with the flame flues of the respective heating walls; each of said heating walls having its vertical flame flues disposed in upper and lower flue sections operable concurrently for downflow combustion and which respectively have rich fuel gas conduits and air regenerator conduits communicating therewith at the

low said distillate gas offtake means and above said means for introducing a fluid medium and adapted for offtake from said coking chambers, separately from and independently of gas off-flow through the distillate-gas offtake means for the coking chambers, of said lean combustible gas; and means for leading gas from said lean gas offtake means directly to the upper ends of the upper and lower sets of vertical flues of said heating walls.

11. In a vertical retort battery for the carbonization of coal, in combination: a plurality of side-by-side continuous vertical coking chambers each adapted to receive through its top substantially continuously the charge to be coked and to discharge through its bottom substantially continuously the coked charge; heating walls therefor between and contiguous to said coking chambers and respectively comprising combustion flues; regenerators communicably connected with the combustion flues of the respective heating walls; one of the heating walls for one of said coking chambers having its combustion flues disposed in upper and lower flue sections which respectively have fuel gas conduits and air regenerator conduits, adapted for separately regulating the heating of said sections so that the upper portions of the coking chamber may be regulably heated for coal gas production and the lower portions for production of a leaner gas formed by reaction of incandescent coke in said retorts with a fluid medium introduced therein; distillate-gas offtake means communicably connected with the upper portions of said coking chamber for offtake of coal-gases of distillation at the upper parts of said coking chamber; means for introducing a fluid medium into the lower portions of said coking chamber for reaction with incandescent coke therein to produce a leaner gas than coal gas in the lower portions of said coking chamber; and lean gas offtake means communicably connected with said coking chamber below said distillate-gas offtake means and above said means for introducing a fluid medium and adapted for offtake from said coking chamber, separately from and independently of gas off-flow through the distillate-gas offtake means for the said coking chamber, of leaner gas produced in the lower portion of said coking chamber from said fluid medium.

posed in upper and lower flue sections which respectively have fuel gas conduits and air conduits, adapted for separately regulating the heating of said sections so that the upper portions of the coking chamber may be regulably heated for coal gas production and the lower portions for production of a leaner gas formed by reaction of incandescent coke in said retorts with a fluid medium introduced therein; distillate-gas offtake means communicably connected with the upper portions of said coking chamber for offtake of coal-gases of distillation at the upper parts of said coking chamber; means for introducing a fluid medium into the lower portions of said coking chamber for reaction with incandescent coke therein to produce a leaner gas than coal gas in the lower portions of said coking chamber; and lean gas offtake means communicably connected with said coking chamber below said distillate-gas offtake means and above said means for introducing a fluid medium and adapted for offtake from said coking chamber, separately from and independently of gas off-flow through the distillate-gas offtake means for the said coking chamber, of leaner gas produced in the lower portion of said coking chamber from said fluid medium.

In witness whereof, I have hereunto set my hand.

JOSEPH VAN ACKEREN.
